HALSEY W. TAYLOR, OF WARREN, OHIO

DRINKING FOUNTAIN

Application filed January 26, 1931. Serial No. 511,181.

My invention relates to drinking fountains, and my object in general is to provide a drinking fountain, having therein or associated therewith, new and improved means 5 for safe-guarding the drinking stream from contamination, all as hereinafter more fully shown and described and more particularly pointed out in the claims.

Thus, in the accompanying drawing, Fig. 10 1 is a sectional view of a drinking fountain basin embodying my improvement, and Fig. 2 a similar view at right angles to Fig. 1.

The invention comprises a bowl or dished basin A of porcelain or other material having means at its top or in its brim for delivering a stream of drinking water upwardly, preferably at an inclination, into the collecting or waste chamber 2 of the basin from the bottom of which the water is adapted to 20 escape freely through a drain pipe 3. The means for jetting the water into the basin may consist of a discharge jet or opening 4 formed in the wall of the basin itself, or a separate delivery nozzle may be mounted 25 within or upon the basin for that purpose according to known practices. In either case, a supply pipe 5 is connected to the basin and jet, and a manually operable valve 6 usually provided to turn the water on and off 30 as needed, although in some installations the water runs continuously. Apart from the provisions usually made for controlling and regulating the supply and drinking stream, I provide other means for automatically cutting 35 off the supply of water when certain undesirable conditions arise which may prove objectionable to the users of the drinking fountain or lead to the contamination of the drinking stream. Thus, I connect a suitable 40 controlling valve 7 to the supply pipe 5, which is open normally but adapted to be closed automatically by valve 7 when the drain inlet or drain pipe 3 is either maliciously or accidentally closed. For example, say that for- 45 eign matter should clog pipe 5 or trap 8, or the strainer plate or inlet 9 be covered and closed, then the water delivered into waste chamber 2 will rise therein until it overflows. In order that the overflow waste water shall 50 not reach the nozzle or jet opening 4 and con-

taminate the drinking stream, I provide a bowl or basin with an offset wall 10 extending beneath a rim portion 11, and form an overflow opening or series of such openings 12 in the wall underneath the rim. This overflow water is then discharged into a separate drip pan or vessel 14 suspended by a bail or handle 15 from the hook end 16 of a lever or arm 17 attached to a rotatable plug or other shut off member 18 forming part of valve 7. 60

The present basin A includes a flanged rear part 20 adapted to be fixed to a wall or other suitable support, and a contracted skirting or apron 21 extends downwardly from the main side walls 22 of the basin to provide a round well or opening at the bottom or beneath the basin, within which the receiver or vessel 14 may be seated. This vessel may be either shallow or deep, and its flanged rim 23 may be made to conform to the shape of the seating edge of the opening at the base of the apron or skirting 21. A coiled spring 24 is connected to a short arm 25 on pivoted lever 17 to hold the valve normally open and also keep the overflow receiver or vessel 14 in its raised and seated position against skirting 21. Accordingly, should the drain opening or pipe of the basin become clogged or closed and the water rise in the basin and overflow through the openings 12, then this waste water will flow downwardly over the curved rear wall 25 and into receiving vessel 14. The added weight of the water to this vessel will overcome the tension of spring 24 and tilt lever 17, thereby closing valve 7 and cutting off the water automatically to jet 4. 70

Summarizing, it will be readily seen that should waste or soiled water collect in the basin its rise to a higher level will be limited or checked by the presence of the overflow openings 12, and when that level is reached and overflow of water occurs that the water supply will then be positively cut off and further operation and use of the fountain absolutely prevented. In other words, the waste water is checked in its rise initially so that it will not reach the higher level occupied by jet 4 and contaminate the drinking stream issuing from the jet, and secondly, the over-flowing water is then utilized to shut off the 80 85 90 95 100

drinking stream and stop further flow of water at the jet automatically. This inventive concept may be carried out in other ways and by other means than as exemplified herein, and various modifications of the invention may be made in view of such disclosures, particularly in details of construction of the basin, the type of valves and kind of stream-forming devices used, in the general assembly and proportioning of parts, etc. Consequently, it should be understood that the present invention is not necessarily limited to the exact form of structure and operating assembly of parts exemplified herein, but includes and embraces all changes and modifications thereof which may be permissible in view of known practices and the prior art.

What I claim is:

1. A basin having an overflow opening 20 therein and a depending skirt having an opening at the base thereof, a water delivery device for said basin having a controlling valve, and an overflow receiving vessel connected to said valve and having a flanged rim conforming to the shape of and seated in closure engagement with said skirt, and closing said opening.
2. A basin having a drain opening at its bottom and an overflow passage at one side, 30 and including a stream-projecting device located within said basin in a higher plane than said overflow passage, in combination with a water supply pipe connected to said stream-projecting device, a rotatable valve 35 for controlling the flow of water through said pipe, a water receiving vessel, and spring actuated means rigidly connected with the rotatable part of said valve for holding the valve open and for yieldingly 40 suspending the said vessel in position to rotate and close said valve when water overflows into the vessel.
3. A basin having a depending skirt formed with an opening at the base thereof, 45 said basin having an overflow communicating with said base opening, a water delivery device for said basin having a controlling valve, and an overflow receiving vessel shaped to fit the opening in the base of said 50 depending skirt, said valve including spring actuated means tending to open said valve and suspending said vessel for movement to and away from closing position with respect to said base opening.

55 In testimony whereof I affix my signature.
HALSEY W. TAYLOR.
